PAUL GRUND, OF BERLIN-TREPTOW, GERMANY, ASSIGNOR TO THE FIRM MINIMAX
G. M. B. H., OF BERLIN, GERMANY

AUTOMATIC IGNITING DEVICE FOR FLAME-THROWING APPARATUS

Application filed August 20, 1928, Serial No. 300,940, and in Germany August 23, 1927.

My invention relates to flame throwers or torches in which a combustible liquid is burned upon leaving a nozzle through which it is forced, and more particularly it relates to automatic igniting devices for such flame throwers.

The object of my invention is to provide a reliable igniting device for such flame throwers, which will not be put out of order by moisture or other uncontrollable influences and which is moreover inexpensive, of light weight and easy to handle.

The igniters used heretofore for such purposes utilized electric ignition, or an oxy-hydrogen gas or other flame was temporarily or continuously maintained near the nozzle for igniting the combustible liquid as it leaves the nozzle. These ignition methods have the disadvantage that they do not work reliably, especially when intermittent operation of the flame thrower is required. Besides that, the weight of igniters of this kind makes it very difficult for the operator to hold the nozzle for any long period. Furthermore, the electric ignition is very easily put out of order by moisture or, if an igniting flame is used, the small openings of the burner become very easily clogged by earth or impurities.

According to the present invention, the impact of the liquid being pressed through the flame thrower nozzle, when the apparatus is started, pushes forward a piston which is connected to a number of friction fuses, thereby actuating the friction fuses and igniting the valenciennes surrounding the tube in which the piston is guided and which valenciennes in turn ignite the liquid flowing through the tube after the piston has been pushed out by its impact.

With the present invention, any light weight nozzle can be used for directing the jet of burning liquid as e. g. oil. For the continuous ignition of the jet leaving said nozzle, it is sufficient to arrange in front of the nozzle an igniter according to the invention and this may be accomplished, for instance, by inserting the igniter into an igniter holder fastened to the nozzle. This igniter holder, which is not part of the invention, can be designed in such a manner that the igniter

is automatically removed from the holder by springs or similar means so that it is not necessary to touch it with the hands. Thereupon a new igniter kept ready by the operator is inserted into the igniter holder. According to the invention, each igniter contains a complete mechanism for the ignition of its valenciennes so that it is unnecessary to provide any further devices for the ignition of the liquid.

The drawing shows one embodiment of the invention, of which Fig. 1 is a cross section on line 1—1 of Fig. 2 and Fig. 2 is a longitudinal section on line 2—2 of Fig. 1.

In the drawing, N is the nozzle of a freely movable flame thrower tube which is connected to a vessel, not shown in the drawing, the oil jet to be ignited flowing through opening K of the nozzle. The igniter is fastened to the flame thrower nozzle in any suitable manner, for instance, by screwing or by inserting it into an igniter holder of the kind mentioned above. These fastening devices are not shown in the drawing as they are not part of the present invention. The igniter consists of a tube O in which slides a piston member A and which is surrounded by a second tube P. The inertia of the oil jet leaving nozzle N when the flame thrower is started, drives piston A forward in tube O, a disk C being employed, if desired, to make a tighter contact with the walls of the tube. A cross piece B is connected to the piston and actuating wires L for the operation of the friction fuses D, of well known construction, are fastened to said cross piece B. Any desired number of friction fuses may be provided—the drawing shows two of them—and they are put into operation when piston A is driven forward in tube O by the pressure of the liquid leaving the nozzle whereby the piston carries with it cross piece B and wires L. The ends S of the wires L are of such a size as to be prevented from passing out of the interior of the friction fuses D, a sufficient length of the wire L being contained within each fuse so that upon withdrawal of that length friction occurs between the wire L and the material within the fuse D. This friction causes the desired ignition of the

friction fuses D. The friction fuses ignite a priming composition M with which they are provided and which in turn ignites valenciennes (not shown) arranged within the annular cavity G between tubes O and P. Friction fuses D are soldered to socket F with soft solder J, as shown in Fig. 2, which is melted by the heat developing during the ignition. The sockets F are held between the tubes 10 O and P by solder R. Therefore, fuses D can follow the pull exerted upon them by piston A over cross piece B and wires L so that the piston can be thrown off by the jet of liquid under pressure. The jet can now 15 freely flow through tube O and is continuously ignited by the flame which burns now vividly in front of the igniter.

In order to protect the outside tube P against destruction through the heat developed by the burning valenciennes, it is provided with an asbestos lining H. The front end of the ignition device may be provided with a cap E which prevents injury to the igniter during storage, caused by moisture. 25 This cap is also thrown off by the advancing piston A.

After the igniter is fastened on the flame thrower nozzle, the operation is as follows: Upon the oil jet being turned on, the piston 30 A together with the cross piece B will be forced outwardly. The cross piece B will draw the wires L from the fuses D until the ends S are prevented from passing out of these fuses. Due to the friction between the 35 wires L and the material in the fuses D the required ignition of these fuses occurs. The heat generated by the ignition of these fuses in turn ignites the priming composition M which in turn ignites the valenciennes in the 40 cavity G. Through the heat generated through the burning of the composition M the soft solder J is melted. Since the piston A is still under pressure from the oil jet, it is now free to be thrown off carrying with 45 it the cross piece B, the wires L, burnt out fuses D, and the cap E. The valenciennes having been ignited by the composition M now projects a flame through the openings left by the removal of the fuses D. The jet 50 of oil passing out through the open end of the tube O is ignited by this flame.

If the valenciennes is burnt out, the igniter can be removed from its holder, after the liquid supply has been shut off, a new igniter 55 inserted and the flame thrower is again ready for operation.

Having thus described my invention, what I claim is:

1. In a flame thrower igniting device, an 60 igniting composition around the flame thrower nozzle for continuously igniting the flame thrower liquid, fuses for igniting the igniting composition and fuse-operating means actuated by the jet of the flame thrower 65 liquid upon leaving the nozzle.

2. An igniting device which can be interchangeably fastened to the nozzle of a flame thrower, consisting of valenciennes concentrically arranged around the nozzle, of fuses for the ignition of the valenciennes and of 70 mechanical means operated by the jet of flame thrower liquid upon leaving the nozzle, for the ignition of said fuses.

3. An exchangeable flame thrower igniting device consisting of a set of two concentric 75 tubes adapted to be fastened upon a flame thrower nozzle coaxially with the nozzle and containing between their walls valenciennes for maintaining the combustion of the flame thrower liquid, a piston sliding within the 80 innermost of said concentric tubes, friction fuses connected to the valenciennes by means of a priming composition and mechanically connected to the piston in such a manner that the piston upon being advanced by the liquid leaving the nozzle actuates the friction fuses and ignites the valenciennes.

4. A device according to claim 3, with the valenciennes containing tubes, the piston and the fuses being arranged in such a manner that the piston and fuses are thrown off by the jet of flame thrower liquid after ignition has taken place.
